UNITED STATES PATENT OFFICE.

ROBERT J. BAKER, OF DENVER, COLORADO.

SEAL.

1,163,124.

Specification of Letters Patent.

Patented Dec. 7, 1915.

Application filed January 20, 1915. Serial No. 3,286.

To all whom it may concern:

Be it known that I, ROBERT J. BAKER, a citizen of the United States, residing at Denver, in the county of Denver and State of Colorado, have invented new and useful Improvements in Seals, of which the following is a specification.

The present invention relates to improvements in bag seals, such as money bag seals, of the general type disclosed in my prior Patent #837,535, dated December 4, 1906; and one object of the present invention is to provide a seal which is simple and inexpensive in construction, capable of being applied with ease and facility, and incapable of being removed or tampered with without giving visual evidence of that fact.

A further object of the invention is to provide a seal including a needle and a binding tie, together with a seal body adapted to receive a fusible sealing substance, such as wax or metal, to hold the tie bound and adapted to be impressed with the name or seal-mark of the bank, corporation, firm 25 or person filling and sealing the bag.

The invention consists in the features of construction, combination and arrangement of parts hereinafter described and claimed, reference being had to the accompanying 30 drawings constituting a part of this application, in which:

Figure 1 is a perspective view of a form of seal embodying my invention; Fig. 2 is a sectional view taken through the neck 35 portion of a bag, showing the needle and tie applied ready for the final sealing operation; Fig. 3 is a perspective view of the sealed bag; and Fig. 4 is a cross section through the seal-body.

In carrying my invention into practice, I provide a seal body 1, preferably comprising a circular body of sheet metal or other suitable material, said body being formed of a base 2 provided with an upstanding 45 marginal flange 3, inclosing a space or chamber 4 designed to receive a sealing medium, as hereinafter described. The shallow chambered body or receptacle 1 is provided at diametrically opposite sides in its flange 50 3 with openings 5 and 6, and adjacent to the respective openings 5 and 6 are other openings 7 and 8 placed on opposite sides thereof. The side of the flange which is provided with the openings 5 is also provided with still another opening 9. The 55 openings are arranged in the vertical wall

of the flange, which is formed with an in-turned stiffening and retaining bead 10.

Extending through the openings 5 and 6 in the flange of the body 1 is a needle 11 terminating at one end in a flattened eye or perforated point 12, and which projects and is disposed a suitable distance beyond the side of the flange 3 provided with the opening 6. At its opposite end the shank 60 or stem of the needle projects a distance beyond the diametrically opposite side of the flange 3 through the opening 5, and this end of the needle is connected by a loop or eye 13 with a spring retaining arm 14 extending into the chamber 4 through the opening 9.

In practice, the needle and its retaining arm are preferably made as a whole of a single piece of spring or other wire and are 75 applied to the body 1 in an obvious manner by inserting the needle body and the retaining arm through the holes 5, 6 and 9. The arm 14, it will be observed, lies at an angle to and crosses the needle stem or 80 shank and hence closes the loop 13 and acts to frictionally bind the adjacent portions of the needle against the walls of the openings 5 and 9 to retain the needle in position against possibility of displacement. It 85 will be evident that the needle cannot be dislodged or withdrawn without bending the retaining arm back to permit the needle to pass outward through the openings 5 and 9, so that accidental detachment of the needle from the body 1 cannot possibly occur. In practice, the loop or eye 13 is provided to hold an address tag or the like 14, but this outwardly extending loop or eye may be omitted if desired. 95

In employing the improved seal the neck portion of a bag 15 is gathered in the usual manner, and then the needle is thrust through the gathered neck portion of the bag, as shown in Fig. 2. The ends of a tie 16 of cord or wire are then brought around the neck of the bag to form a loop and then passed through diametrically opposite sets of openings 7 and 8, and drawn tight to hold the neck tightly closed and the seal body 1 100 pressed against the same, the parallel strands of the tie thus being extended across the interior of the chamber 4. Finally, the seal is completed by filling the chamber 4 up to the level of the inturned bead 10 with a suitable binding and sealing material 11, such 105 as sealing wax or metal fusible at a low tem-

perature, as Babbitt metal, in which the inclosed portions of the needle and tie cord or wire are embedded and sealed. While the material 11 is still soft the face thereof showing through the open side of the chamber 4 may be impressed, by means of a suitable seal, with the name or title of the bank or other concern filling and shipping the bag.

It will be observed that the fusible binding medium 11 will not only hold the needle and tie from accidental displacement, but will effectually prevent any attempt to open the bag or break the seal without detection, since the seal cannot be removed without destroying the binding medium 11 and thus giving visual evidence of the fact that the seal has been tampered with. Furthermore, the impression upon the face of the fusible binding medium gives additional security, while the bead 10, in addition to stiffening the body 1 and permitting of its inexpensive manufacture of sheet metal, also serves to stay the binding medium 11 and to assist in holding it in position.

Having thus described my invention, I claim:

1. A seal comprising a body forming a shallow receptacle open at one side and having its side wall provided with an in-turned bead over-hanging the chamber of the receptacle, a needle having a shank extending through said side wall and across the chamber of the receptacle, a tie threaded through and across the receptacle and engaging the eye of the needle, and a plastic binding medium within the chamber extending marginally beneath the bead and in which the inclosed portions of the needle and tie are embedded.

2. A seal comprising a circular body forming a shallow chamber open at one side, said body including a side wall bounding said chamber and provided with an inwardly projecting bead over-hanging the same, a needle extending across said chamber and extending through said side wall, a tie looped at one end and engaged with the eye of the needle and having strands extending parallel with and on opposite sides of the needle shank and through diametrically-opposite sides of the side wall, and a plastic binding medium within said chamber and underlying said bead and covering the inclosed portions of the needle and tie.

3. A seal comprising a shallow circular receptacle having an upstanding flange pro-

vided at diametrically opposite sides with pairs of openings, a needle fixed to said flange between the openings of the respective sides and having an eye projecting beyond the receptacle, a tie extending through said openings and engaging the eye of the needle, a filling of fusible binding material within the receptacle and investing the inclosed portions of the needle and tie, and retaining means upon said flange overhanging said filling.

4. A seal comprising a shallow receptacle embodying a bottom and an upstanding flange, said flange being formed with a pair of openings at one side and two pairs of openings at its opposite side, a needle having a stem or shank passing through an opening in each side and projecting at one end and provided with an eye, the other end of said needle being formed with a loop and having a retaining arm extending through one of the four openings at the adjacent side at an angle into the receptacle, a tie having strands passing through the other openings at the opposite sides of the flange parallel with the shank of the needle and connected at one end by a loop passing through the eye of the needle, and a body of fusible material within the receptacle and in which the needle and tie are embedded.

5. A seal comprising a shallow circular receptacle formed of a bottom and an upstanding flange provided with an inturned bead, a needle extending across the chamber of the receptacle and having a looped portion at one end projecting through and laterally beyond one side of the flange and having an eye at its opposite end projecting through and laterally beyond the opposite side of the flange, a tie looped at one end and engaged with the eye of the needle and having strands extending through the flange of the receptacle and the chamber thereof in proximity to the shank of the needle, and a filling of a plastic binding medium within said receptacle and underlying said bead and covering the inclosed portions of the needle and tie.

In testimony whereof I affix my signature in presence of two witnesses.

ROBERT J. BAKER.
